G. Copeland,

Imp. Loom-Harness Clasp.

N° 11,719.

Patented Sep. 26, 1854.

UNITED STATES PATENT OFFICE.

GEORGE COPELAND, OF DANVILLE, MAINE.

CLASP FOR LOOM-HARNESS.

Specification of Letters Patent No. 11,719, dated September 26, 1854.

To all whom it may concern:

Be it known that I, GEORGE COPELAND, of Danville, in the county of Androscoggin and State of Maine, have invented a new and useful Clasp for Attaching Weavers' Harness to the Straps by which it is Suspended; and I do hereby declare that the following is a full, clear, and exact description of the same, reference being had to the accompanying drawings, forming part of this specification, in which—

Figure 1, is a front view, showing one of the clasps, the strap and a portion of the upper harness shaft and harness. Fig. 2, is a transverse section of the same. Fig. 3, is a front view of part of the shaft and harness with the clasp and strap in section.

Similar letters of reference indicate corresponding parts in the several figures.

20 My invention consists in two plates which are placed, one in front of the harness shaft, and the other behind it, and furnished with teeth or catches which pass between the heddles, on the under or inner side of the shaft, 25 and are so suspended from the strap that its tension draws them toward each other, and causes the shaft to be confined between them. This clasp affords a cheaper and more convenient mode of attaching the harness, and prevents injury to the shafts or heddles, and thereby renders the harness more durable than when attached to the straps in the old way.

To enable those skilled in the art to make 35 and use my invention, I will proceed to describe its construction and operation.

A, A, are the plates forming the clasp, which I prefer to make of cast iron for the sake of cheapness, but which might be of 40 other metal. They are both cast from the same pattern, having teeth or catches a, a, at one extremity, which are thin enough to pass between the heddles, and of a length about equal to the thickness of the harness 45 shaft, and having two openings b, b', of sufficient size to allow the strap B, to pass freely through, the holes b, b', being far enough from the catches or teeth a, a, to leave room between them and the said 50 catches or teeth to receive the harness shaft or heddle rail D. The strap is looped, and each side of the loop passes through the hole b, of one plate, then outside the bar c, which is left between the two openings, through

the opening b', and inside the bar d, which forms the end of the plate. The loop is secured by a buckle C, or other fastening, and the tension of the strap acts so as to draw the toothed ends of the plates toward each other. The two plates may be considered as levers of the first order with the bars c, c, as the fulcrum and the power applied by the strap inside d, d, or as levers of the third order, with d, d, as the fulcrum, and the power applied outside c, c. The 65 teeth or catches a, a, are so placed, that those of one plate are about opposite the centers of the spaces between those of the other plate.

This clasp affords the greatest facility for 70 attachment and detachment of the harness to and from the strap, as when the strap is slack, the plates hang free to be moved apart, as shown in red outline in Fig. 2. Besides being cheaper than the hook and 75 eye commonly used for attaching the shaft or rail to the strap, it possesses several advantages. 1st. It allows the web to be adjusted sidewise in the loom without boring holes in the shaft, while the eyes require 80 new holes for every adjustment. 2d. The harness is not crowded over to make room for the eye and therefore not apt to cant the heddles. 3d. It causes no injury to the shafts by the changing of the harness, 85 while the changing of the eye, which is often necessary, in order to make the web hang true, frequently renders the shaft unfit to be re-knitted upon. 4th. The tin band for holding the two sides of the loop together, is dispensed with. 5th. The clasp can be applied to any part of the harness instantly. 6th. It is stronger and more secure, and 7th. It gives more room to buckle up, 90 as it leaves a greater length of strap between 95 the harness and the roll.

What I claim as my invention, and desire to secure by Letters Patent, is:—

The clasp formed of two plates A, A, having holes b, b', to receive the strap, and 100 catches teeth a, a, or other analogous projections to catch the harness shaft or rail, substantially as herein described.

GEORGE COPELAND.
